R. TOENNES

CONCRETE POST

Filed Jan. 2, 1925

Inventor

Richard Toennes

By Edwin L. Yewell

his Attorney

UNITED STATES PATENT OFFICE.

RICHARD TOENNES, OF BOONVILLE, MISSOURI.

CONCRETE POST.

Application filed January 2, 1925. Serial No. 203.

To all whom it may concern:

Be it known that I, RICHARD TOENNES, a citizen of the United States, residing at Boonville, in the county of Cooper and State of Missouri, have invented certain new and useful Improvements in Concrete Posts, of which the following is a specification.

This invention relates to improvements in concrete fence-posts and has for its objects to provide a strong and durable post having a means for readily attaching the fence-wires thereto and holding them taut and in spaced relation with each other without the use of tie-wires for the individual strands.

These and other objects hereinafter set forth are attained by the means illustrated in the accompanying drawing, in which:—

Figure 1 is a perspective view of the improved post showing several different types of wires attached thereto.

Figure 2 is a cross-sectional view through the post.

Figure 3 is a detail perspective view of a portion of the wire supporting helix, and

Figure 4 is a cross sectional view of the molding frame showing the post while being formed and illustrating the manner of embedding the wire supporting helix.

Similar reference numerals in all of the figures of the drawing designate like parts.

This post is constructed of concrete and is formed with an upper tapered portion 10 adapted to support the fence-wires and a lower tapered portion 11 adapted to serve as a base and be buried in the ground, the taper of the upper portion being inward toward the upper end of the post from an intermediate point and the taper of the lower portion being inward toward its lower end from the same intermediate point, thus making this intermediate point the largest cross-section area throughout the length of the post and designating the ground line thereof.

The post is preferably triangular in cross-section throughout its entire length and has projecting from one of its flat faces a pair of longitudinal ribs 12 having sharp wire engaging edges formed at the opposite edges of said flat face and which preferably extend the full length of the post as shown in the drawing, but it is understood that these ridges may terminate adjacent to the ground line of the post.

Partially embedded in the post is a wire helix 13 the coils of which lie relatively close together, say, approximately two inches apart, and with the unembedded portion of the coils projecting beyond the front-face 14 of the post to a point substantially in alignment with the longitudinal edges 15 of the ridges 12 for a purpose hereinafter described. This helix 13 preferably extends from the top end of the post to a point somewhat below the ground-line thereof, so that the lower end of said helix will extend below the surface of the ground when the post is set up in position. Also embedded throughout the length of the post are the reinforcing rods 16 which are preferably located adjacent the corners thereof.

A lock-rod 17 is provided for retaining the fence in position against the post, said lock-rod being adapted to have its ends 75 turned over to form hooks 18 which serve to retain it in engagement with the coils of the helix.

A longitudinal groove 19 is also formed in the front-face of the post for a purpose 80 hereinafter set forth.

In assembling the fence, the longitudinal fence-wires are drawn taut across the front-face of the post engaging the longitudinal edges 15 and lying between the exposed coils 85 of the helix, and owing to the position of the outsides of the coils with reference to the vertical edges 15 of the ridges 12, it is necessary to slightly bend the fence-wires inwardly between said ridges, as indicated at 90 20, to permit the passage of the lock-rod 17 between the fence-wires and the inner side of the unembedded portion of the coils.

The close arrangement of the coils permits the use of any kind of fence-wire, 95 either barbed, perfectly smooth, or woven, as shown in Figure 1 of the drawing, and should a barb of the fence-wire, or a crossing of the woven wire, be accidentally positioned at or near the lock-rod position, said barb or 100 crossing can be bent into the groove 19, as shown by dotted lines in Figure 2. Furthermore, the close arrangement of the coils permits the use of a relatively light-weight lock-rod, as the bearing-points of the coils 105 against the lock-rod are too close to permit the lock-rods bending outwardly between the coils under the tension of the fence-wires, so that, at all times the lock-rod remains straight thereby permitting its easy with- 110

drawal after its lower locking-hook 18 is bent into alinement with the rod.

The kinking or bending of the fence-wires at the connecting points on the posts between the sharp wire engaging edges of the ridges prevents the pulling of the wires through the post connections, thus preventing sagging between the posts, and the extension of the helix below the surface of the ground acts as a lightning conductor for the fence.

The form of post described is easy to mold, is-economical in material, and also strong and durable. It is cast in a V-shaped mold which is first filled up to the line *a--a* (Figure 4), then the lower rod 16 is laid in place, more concrete is added up to line *b--b*, and the upper rods 16 are positioned, then the mold is filled to its top edges and the ridges formed preferably by trowelling. At this time, when the concrete is soft and plastic, the wire-helix is forced into the soft material, and to prevent distortion of the coils of the helix while it is being forced into position, a bar 21, preferably oval in cross-section, is placed within the whole length of the helix and the forcing pressure is applied thereto, thereby forcing all of the coils simultaneously into the concrete and preventing distortion. After the helix has been forced into the concrete the desired distance, the rod 21 is gradually worked upwardly from engagement with the coils and

thus working the concrete over the embedded portion of the coils, it is then bodily removed from within the helix leaving the groove 19 in the face of the post.

Having thus fully described the invention, what is claimed is:—

1. A concrete post of triangular cross-section provided with a front-flat face and having a fence-wire supporting-means projecting centrally from its front-flat-face, projecting ridges having sharp wire engaging edges formed at the longitudinal edges of said front-flat-face at each side of said supporting means, the extreme outer edges of said ridges and the outer sides of said fence-wire-supporting means lying substantially in alinement, and a lock-rod for engaging between the outer-sides of the fence-wire-supporting means and the fence-wires.

2. A concrete post of triangular cross-section having a wire helix partially embedded therein, the outer sides of the coils of said helix being projected centrally from the front-flat-face of the post, ridges projecting along both sides of said front-face the extreme outer edges of which lie substantially in alinement with the outer sides of the coils, and a lock-rod for engaging between the outer sides of the coils and the fence-wires.

In testimony whereof I affix my signature.

RICHARD TOENNES.
